ROCK BIT

Matthew H. Arnold, Los Angeles, Calif.

Application December 13, 1935, Serial No. 54,235

4 Claims. (Cl. 255—64)

This invention relates to a drilling tool and relates more particularly to a rock drill for use in mining, quarrying and the like. A general object of this invention is to provide a practical, effective rock drill embodying a detachable and replaceable bit or cutting head.

Another object of this invention is to provide a rock drill embodying a drill rod and a detachable cutting head connected and related so that the drilling blows and forces are transmitted directly from the drill rod to the cutting head by large contacting surfaces lying in planes at substantially right angles to the longitudinal axis of the drill.

Another object of this invention is to provide a rock drill of the character mentioned in which rotation is directly transmitted from the drill rod to the cutting head by extensive cooperating surfaces of the rod and head.

Another object of this invention is to provide a rock drill in which the cutting head may be easily and quickly detached from the drill rod for replacement and resharpening.

Another object of this invention is to provide a rock drill that embodies a single simple securing member removably connecting the head with the drill rod, which member does not transmit the drilling forces between the rod and head and, therefore, is not distorted or made difficult of removal.

Another object of this invention is to provide a rock drill that does not become caught or stuck in the drill bore by accumulations of cuttings.

Another object of this invention is to provide a rock drill that embodies novel means for discharging the circulation fluid in a manner to prevent the accumulation of cuttings about the cutting head and drill rod.

A further object of this invention is to provide an improved rock drill of the character mentioned that is simple and inexpensive.

The various objects and features of my invention will be fully understood from the following detailed description of typical preferred forms and applications of the invention, throughout which description reference is made to the accompanying drawing, in which:

Fig. 1 is a side elevation of one form of the drill provided by this invention showing the principal parts in longitudinal cross section. Fig. 2 is a bottom elevation of the drill being a view taken as indicated by line 2—2 on Fig. 1. Fig. 3 is a transverse detailed sectional view taken as indicated by line 3—3 on Fig. 1. Fig. 4 is a side elevation of the cutting head apart from the

drill rod and Fig. 5 is a longitudinal detailed sectional view of another form of the invention.

The rock drill provided by this invention illustrated in Figs. 1 to 4, inclusive, of the drawing, includes, generally, a drill rod 10, a bit or cutting head 11 and means 12 for removably securing the head 11 to the rod 10.

The drill rod 10 is provided to carry the cutting head 11 and to transmit the impact or drilling forces to the head. The rod 10 is an elongate member and its length may depend upon the character of the work or drilling operations. In accordance with the invention the end portion of the rod 10 which carries the head 11 is oval or polygonal in transverse cross section. If desired, the rod 10 may be of such configuration throughout its length. In the particular form of the invention illustrated in the drawing the rod 10 is hexagonal in transverse cross section. In accordance with the invention the end 13 of the drill rod 10 is flat and at right angles to the longitudinal axis of the rod. A central longitudinal fluid passage 14 is provided in the drill rod 10 and extends through the rod from one end to the other.

The bit or cutting head 11 is the active or cutting element of the drill and is detachably secured to the rod 10 by the means 12. The cutting head 11 is a simple, integral member whose inner or upper portion may be substantially cylindrical as illustrated in the drawing. The outer or lower portion of the head 11 has a flaring or convergent exterior 15 so that the active end of the head is larger in diameter than the drill rod 10.

The active face or cutting face of the head 11 preferably lies in a plane substantially normal to the longitudinal axis of the drill and is provided with suitable cutting parts or teeth 16. In the particular case illustrated in the drawing the teeth 16 are straight and are substantially radial.

It is to be understood that the cutting head 11 may be provided with teeth or cutting parts of any suitable character or configuration. It is preferred to hard face the teeth 16 and the lower end of the head 11 or to provide the cutting faces of the head with hard wear resisting material. In accordance with the invention a socket 17 is provided in the head 11 to receive the end portion of the drill rod 10. The socket 17 is of substantial depth and is shaped to accurately or properly receive the polygonal rod 10. Where the rod 10 is hexagonal as illustrated the socket 17 is of corresponding configuration. The bottom wall 18 of the socket 17 is flat and normal to the longitudinal axis of the drill to cooperate with the

end 13 of the drill rod 10. It will be apparent how the end 13 of the drill rod 10 cooperating with the bottom wall 18 of the socket 17 directly transmits the drilling forces from the rod 10 to 5 the cutting head 11. In a similar manner the sides of the polygonal drill rod 10 cooperate with the flat walls of the polygonal socket 17 for the transmission or rotation from the rod to the head 11.

10 The means 12 for removably securing the cutting head 11 to the drill rod 10 dependably and rigidly secures the head to the rod and yet permits the easy rapid removal of the head 11 after 15 operation of the drill. The securing or connecting means 12 includes or provides a socket 20 in the end portion of the drill rod 10 and an opening 21 in the head 11. The socket 20 and the opening 21 are preferably co-axial with the central longitudinal axis of the drill and are, therefore, in 20 axial alignment. The means 12 comprises a single bolt or connecting member 22 extending through the opening 21 and threaded into the socket 20. The threads of the socket 20 and the connecting member 22 are preferably left-hand 25 threads. A head 23 is provided on the outer end of the connecting member 22 and is received in a socket or counter-bore 24 at the outer end of the opening 21. The inner face of the head 23 and the inner wall of the counter-bore 24 may be 30 tapered as illustrated. A polygonal wrench socket 25 is provided in the head 23 to facilitate the threading of the connecting member 22. The head 23 of the connecting member 22 is recessed or countersunk in the counterbore 24 beyond the 35 active parts or teeth 16 of the cutting head 11 and may be provided with an annular cutting edge 23a for engaging the central part of the rock or work. Threading or tightening of the connecting member 22 in the socket 20 securely attaches 40 the cutting head 11 to the drill rod 10 to hold the bottom wall 18 of the socket 17 in cooperation with the end 13 of the drill rod 10.

The invention provides novel and particularly effective means for discharging the circulation 45 medium or fluid to flush the cutting teeth 16 and to carry the cuttings away from the head 11 and the rod 10. In accordance with the invention the bolt or connecting member 22 is tubular, having a central longitudinal opening 26. The upper end 50 of the opening 26 directly communicates with the fluid passage 14 and the lower end of the opening 26 discharges downwardly through the wrench socket 25. A groove 27 surrounds the connecting member 22 at the contacting rod end 13 and 55 socket bottom 18. In practice the groove 27 may be formed in both the bottom of the socket 17 and the end of the drill rod 10. One or more lateral ports 28 are provided in the connecting member 22 to place the groove 27 in communication with 60 the fluid opening 26. Substantially radial fluid channels 29 extend outwardly from the annular groove 27. In the particular structure illustrated in the drawing there are two fluid channels 29 provided in the bottom wall 18 of the socket 17. 65 Discharge channels 30 extend from the outer ends of the radial channels 29 to discharge the fluid at the upper or inner end of the cutting head 11. Where the radial channels 29 are provided in the head 11 it is preferred to also provide the discharge channels 30 in the head, it being understood 70 that the channels 29 and 30 may be formed in the drill rod 10, if desired. The ports 28, the groove 27 and the channels 29 conduct fluid from the opening 26 to the channels 30 and the channels 30 discharge this fluid axially along the drill 75

rod 10 at the outer end of the head 11 to carry the cuttings away from the cutting head 11 and the end portion of the rod so that the cuttings do not accumulate about the head and rod.

In the operation of the drill provided by this invention the drilling forces are transmitted directly from the drill rod 10 to the head 11 through the contacting surfaces 13 and 18 while the drilling or turning forces are directly transmitted from the rod 10 to the head 11 through the contacting side surfaces of the rod 10 and the side walls of the socket 17. Thus the connecting member 22 does not transmit any of these forces and, therefore, is not subject to wear or distortion. The connecting member 22 dependably connects the head 11 to the rod 10 without becoming loosened. The fluid discharged from the opening 26 fully flushes the teeth 16 and carries the cuttings away from the active end of the head 11 while the fluid discharged from the channels 30 carries the cuttings away from the head and the inner end of the rod 10 to prevent the cuttings from accumulating about the head. Accordingly, there is little or no tendency for the drill to become stuck or caught in the drill bore. When the cutting teeth 16 become dulled or when it becomes desirable to replace or recondition the cutting head 11, the head may be easily removed from the drill rod 10. To remove the cutting head 11 from the rod 10 the connecting member 22 is unthreaded from the socket 20 and is removed from the socket and the opening 21. Due to the fact that the connecting member 22 is not subjected to the action of the drilling forces it is easily removed following the use or operation of the drill. 35 Following the removal of the connecting member 22 the cutting head 11 may be easily slipped or removed from the drill rod 10. A new or replacement cutting head may then be arranged on the rod 10 and secured to the rod by the connecting member 22 or by a new or replacement connecting member 22. The drill is then reconditioned for 40 further use. The cutting head 11 and the connecting member 22 are easy and simple to manufacture so that the drill is inexpensive. 45

Fig. 5 of the drawing illustrates another form of the invention embodying a modified or alternative means 12a for removably securing the head 11 to the drill rod 10. The head or bit 11 and the rod 10 may be substantially the same as described above. The securing or connecting means 12a includes a bolt or connecting member 22a passed through the central opening 21 in the bit 11 and threaded into the opening 20 in the rod 10. The member 22a has a polygonal head 23a received in the counter-bore 24 of the bit 11. The head 23a is such that it may be readily engaged by a wrench when seated in the counter-bore 24. In accordance with the form of the invention illustrated in Fig. 5 the head 23a of the connecting member 22a is pointed or provided with a cutting part 40. The cutting part 40 may be pyramidal or conical as illustrated and is adapted to act on the rock or work. The provision of the cutting part 40 adapts the bit for use in drilling asphalt or the like. When the connecting member 22a is threaded in the opening 20 to have its head 23a clamp against the bottom wall of the counter-bore 24 it securely and dependably attaches the bit 11 to the rod 10. A central longitudinal passage or opening 26a enters the connecting member 22a from its upper end and terminates at a point spaced from the head 23a. Lateral ports 28a are provided in the connecting member 22a to communicate with the 70 75

inner portion of the opening 26^a. The ports 28^a place the opening 26^a in communication with the annular groove 27 whereby the circulation fluid may flow from the ports 28^a through the groove 27, the channels 29 and the discharge channels 30. The operation of the form of bit illustrated in Fig. 5 of the drawing is substantially the same as that of the previously described form of the invention, except that the cutting part 40 acts on the central portion of the bore hole and the circulation fluid is only discharged outwardly or rearwardly from the channels 30.

Having described only typical preferred forms and applications of my invention, I do not wish to be limited or restricted to the specific details herein set forth, but wish to reserve to myself any variations or modifications that may appear to those skilled in the art or fall within the scope of the following claims:

20 Having described my invention, I claim:

1. A rock drill comprising, a drill rod, a cutting head having a socket receiving an end portion of the rod to have the end of the rod bear on its bottom wall, there being a fluid passage 25 extending longitudinally through the rod and head to discharge from the active end of the head and a channel between the contacting surfaces of the rod and head communicating with the passage and discharging at the other end of the head, and means removably securing the head to the rod.

2. A rock drill comprising a rod having a fluid passage, a cutting head, the rod and head having telescopically related force transmitting parts,

there being channels between the contacting surfaces of said parts communicating with the passage and discharging into the drill bore at the outer end of the head, and a member removably connecting the head to the rod and having an opening 5 communicating with the passage and discharging at the active end of the head.

3. A rock drill comprising a rod having a fluid passage, a cutting head, the rod and head having telescopically related force transmitting parts, there being channels between the contacting surfaces of said parts and adapted to discharge into the drill bore, and a member threaded into the passage to removably secure the head to the rod and having an opening 10 communicating with the passage and discharging into the bore and having a port carrying fluid 15 from said opening to the channels.

4. A rock drill comprising a polygonal rod having a longitudinal fluid passage, a cutting head 20 having a polygonal socket receiving an end part of the rod and having an opening aligned with the passage, there being a channel between contacting surfaces of the rod and head discharging at the outer end of the head, and a connecting member passed through the opening, threaded into the passage and engaging against the head to removably secure the head to the rod, there being a longitudinal opening in the member 25 receiving fluid from the passage and discharging at the active end of the head and a port in the member placing the channel in communication with the last named opening.

MATTHEW H. ARNOLD.
